(57) **CLAIM**

The ornamental design for a recreational vehicle, as shown and described.

DESCRIPTION

FIG. 1 is a top, front, and right side perspective view of a recreation vehicle embodying our new design in accordance to a first embodiment;

FIG. 2 is a right side elevation view thereof;

FIG. 3 is a left side elevation view thereof;

FIG. 4 is a top plan view thereof;

FIG. 5 is a front elevation view thereof; and

FIG. 6 is a rear elevation view thereof;

FIG. 7 is a top, front, and right side perspective view of a recreation vehicle embodying our new design in accordance to a second embodiment;

FIG. 8 is a right side elevation view thereof;

FIG. 9 is a left side elevation view thereof;

FIG. 10 is a top plan view thereof;

FIG. 11 is a front elevation view thereof; and,

FIG. 12 is a rear elevation view thereof.

The broken lines in the drawings illustrate portions of the recreation vehicle that form no part of the claimed design. The first embodiment is shown with symbolic breaks in the length of the recreational vehicle. The appearance of any portion of the recreational vehicle between the break lines forms no part of the claimed design.
